Primary Examiner — Garth Rademaker*Assistant Examiner* — Melanie Pellegrini(74) *Attorney, Agent, or Firm* — McAndrews, Held & Malloy, Ltd.(57) **CLAIM**

The ornamental design for a customizable bracelet, substantially as shown and described.

DESCRIPTION

FIG. 1 is a perspective view of a customizable bracelet showing my new design;

FIG. 2 is a top plan view thereof;

FIG. 3 is a front elevational view thereof; and,

FIG. 4 is a bottom plan view thereof.

The broken lines shown in the drawings illustrate portions of the customizable bracelet that form no part of the claimed design.
